MOLD FOR CASTING STEREOGRAPHIC PLATES

William F. Huck, Richmond Hill, N. Y., assignor
to R. Hoe & Co., Inc., New York, N. Y., a corporation of New York; Irving Trust Company, permanent trustee

Application February 18, 1932, Serial No. 593,771

10 Claims.

(Cl. 22—5)

This invention relates in general to molds for casting stereotype printing plates and is directed to certain desired improvements over the device disclosed in application of Robert T. Edwards, filed Nov. 18, 1931, Serial No. 575,769.

The object of the invention is to provide a double flat casting mold of the general type above-indicated with improved means for conveniently locking either movable side of a double casting mold for operatively securing same to a coacting fixed mold member as one or the other is swung into position for casting a plate.

Another object is to provide a stereotype mold of the character indicated with improved means for adjusting same to cast plates of different thickness.

Another object is to provide a novel stereotype plate casting mold having two casting chambers that may be engaged alternately by balanced movable means adjusted for conveniently casting plates of different thickness.

A considerable saving of time is effected by using a mold of the type herein indicated after a plate is cast and while the metal is hardening, since the operator may in the interim prepare a second mold for the next casting operation. After this preparatory work is completed, the second mold is closed and simultaneously therewith the first mold is opened. In this manner one operator may cast practically twice the number of plates in a given interim of time that is possible to cast with conventional stereotype molds. The movable mold members are so connected, as will hereinafter appear, that the centre point of a line joining their centres of gravity will move in a substantially horizontal line.

It was also found to be highly desirable in practice to have the movable mold members positioned at a height from the floor best suited for the operator's convenience. In prior constructions the fulcrum on which the oscillating or movable molds were mounted, was positioned either too close or too far above the floor, which in either case was inconvenient for the operator. Furthermore, the prior construction described in the above-referred application of Edwards was in a state of equilibrium only when one of the coacting and movable casting plates was positioned at right angles and the other in parallelism respectively to the fixed mold-casting member. This necessitated the employment of springs or equivalent means as shock absorbers to cushion the heavy movable members which descend with considerable force and increasing momentum, to the normal positions shown in Figure 1. The present

construction affords a balanced, movable stereotype plate-casting assembly in all positions and may be handled and swung with comparative ease by the operator.

It is also an object of the invention to provide a mold for casting printing plates of generally improved construction, whereby the device will be simple, durable and inexpensive in construction, as well as convenient, practical, serviceable and efficient in its use.

In the drawings:

Figure 1 is a side elevational view of an embodiment of my invention;

Figure 2 is a transverse sectional view as seen on the line of the arrow 2 of Figure 1; and

Figure 3 is a vertical elevational view looking in the direction of the arrow 3 of the Figure 1;

Figure 4 is an enlarged fragmentary detail view of parts directly engaged in the casting of a printing plate.

In the drawings wherein similar characters of reference indicate corresponding parts in the several figures of the preferred form of the invention, 4 designates a mold-supporting frame including the side member 5, 6 held in spaced relation by cross members 7, to which a double-faced mold-casting member 8 is fixedly secured in any suitable manner as by screws 9, 10. The fixed mold-casting member 8 is provided with casting surfaces on either side thereof and also with means for self-cooling which is accomplished by circulating fluid in the jackets or pockets 11. Means connected to the frame are provided for adjustably supporting thereon an assembly including a pair of movable mold-casting members 12, 13, so that same may be swung or rocked in order to bring either face thereof in juxtaposition with the fixed mold-casting member 8, while the other face is simultaneously returned to position for preparing another mold. The said means includes shaft 14, 15 secured to the frame and serving as fulcrums or pivots for the movable mold-casting members 12, 13 which latter include similar side members or arms 16, 17 having an offset portion or projection 18, between which shafts 21, 22 secured to the members 12 and 13 respectively are arranged. The shafts 21, 22 are connected by links or members 23 which co-actingly and balancingly connect the two movable mold-casting members 12, 13 for the important functions hereinafter recited including the maintaining of a state of equilibrium or balance for the movable mold members in all positions.

Each of the movable members 12, 13 includes an adjustable cover member 24 having a frame

suitably reinforced, the outer surface of the said cover member 24 forming one of the walls of the casting chamber hereinafter described. The said cover members 24 are adjustably supported by T-bolts 25 secured in cross members or bars 26, 27, the ends of which latter are secured to the arms or side members 16, 17. The cross members are received in slots 28 formed in extensions or hubs 29, 31 of the movable member. The reduced ends 5 of the T-bolts 25 are rotatably secured in small sockets 32 fastened to the inner side of the cover members 24, whereby when the T-bolts are turned, the cover members may be adjusted towards and away from the respective cross members. 10

15 The chambers for casting the printing plates are formed by the space between one of the adjacent faces of the fixed mold-casting member 8 and a cover member or plate 24 of one of the movable mold-members 12, 13. The bottom and sides of the casting chambers are formed by the customary gauges indicated generally at 33 located 20 at the bottom and sides of the casting chambers when same is ready for receiving molten metal 25 mentioned above, will serve as stops to limit the degree of movement of the said cover members.

25 The chambers for casting the printing plates are formed by the space between one of the adjacent faces of the fixed mold-casting member 8 and a cover member or plate 24 of one of the movable mold-members 12, 13. The bottom and sides of the casting chambers are formed by the customary gauges indicated generally at 33 located 30 at the bottom and sides of the casting chambers when same is ready for receiving molten metal as shown in Figure 2.

30 The body portion 33' of each of the gauges 33 is cutaway or shouldered as at 34 and notched as 35 at 35 to accommodate an extension 36 on a slotted T-shaped arm 37. The extension 36 is provided with a lip or projection 38 slidably received in the notch 35 which latter together with the shouldered portion 34, it is understood, preferably extends the entire length of the gauge in order to permit the said gauge to be slid or moved relatively to the arm 37, and is also formed with a slot 39 positioned angularly relatively to the edge of the extension 36. The slot 39 is adapted 40 to slidably and removably receive a stud or head 40 fastened to a screw 41 secured to the body portion 33' of the gauges 33, it being observed that an accurate adjustment of the gauges 33 is afforded by sliding the studs or heads 40 in the 45 slots 39, thus shifting the body portion 33' of the said gauges 33. It will be further noted that when the gauge 33 is slid, the diagonally positioned slot 39 in coaction with the pin 40 will serve to withdraw the lip 38 from or project same 50 into the notch 35, in this manner conveniently permitting the removal of the gauge from the arm 37 and also adapting the device to accommodate gauges of various widths or sizes.

55 As best shown in Figure 2, each of the arms 37 has a slot 37' slidably receiving a screw 42 which is engaged with a hinge composed of a plate or bracket 43 pivotally connected to a second plate or bracket 44 fastened to the cover member 24. A wing nut 45 after the desired adjustment of the gauge 33 is made serves to conveniently clamp the arm 37 on which the gauge 33 is fastened to the movable plate 43 and thus to maintain the said gauge in the operative position desired for 60 casting a printing plate. A spring 46 connected to both hinge plates 43, 44 normally maintains a pressure on plate 43 thus retaining the gauge 33 resiliently or yieldingly in the operative position best shown in Figure 4, it being noted that an 65 end or extremity of the matrix B is received un-

der a shouldered portion 47 of the body portion 33' of the gauge 33. It will now be apparent that the gauges 33 may be conveniently adjusted and held in operative position by means of the slotted arms 37, the angularly positioned slot 39 and co-acting elements to cast plates of various widths and that such adjustment may be effected by the comparatively simple means employed. When desired, the gauge 33 may, by means of the pin 40 and slot 39, as indicated above, be immediately 10 detached from and conveniently replaced on the adjacent movable mold member, after the latter has been swung away from the fixed mold member.

15 To lock the members 12, 13 in the alternate operative positions best shown in Figure 1, a cam 50 is fastened to a stud or shaft 48 rotatably secured in the fixed mold-casting member and having an operating lever 49 fastened thereon. The cam 47 is formed with a pair of arcuate 20 grooves or notches 51, 52 which are adapted to engage alternately pins 53, 54 fastened respectively to the movable members 12 and 13. By inspection of Figure 1 it will be seen that either of the movable mold-casting members can be 25 locked in operative position shown by swinging the operating lever 49 to the left or right to engage the notches 51, 52 with the pins 53, 54. Each of the movable casting members 12, 13 is provided at one end with a sloping channel or passageway 55, communicating with the casting chamber for the reception of molten metal when the movable member is in vertical position. To swing either of the movable members, 12, 13 into the desired position for casting or preparing a 30 plate, a pair of similar handles 56 suitably secured to each of the said movable members and best shown in Figure 3 are provided.

35 The function and general manner of operation of the above device has been in large measure indicated from the foregoing description, it being observed as pointed out above that while the metal is hardening in the vertically positioned movable mold, the horizontally positioned movable mold may be prepared and ready to be 40 swung against the fixed mold member to form a casting chamber for the reception of molten metal. As the movable members have been so pivoted and interconnected as to counterbalance 45 one another, it will be understood that after the handle 49 has been manipulated to release the vertically positioned movable mold-member 13 from the fixed mold-member 8, the handles 56 of either the upper or lower movable member 50 will be grasped and as the former or vertically positioned mold member descends into a horizontal position, the other counterbalanced movable mold-casting member will swing into vertical 55 position or alignment against the fixed member 8. By reason of the mutual balance between 60 the two movable members, the effort required to move same is reduced to a minimum while at the same time the bump or jar which would normally occur without the counterbalancing principle employed, is avoided.

65 I am aware that the invention may be embodied in other specific forms without departing from the spirit or essential attributes thereof, and I therefore desire the present embodiment to be considered in all respects as illustrative and not 70 restrictive, reference being had to the appended claims rather than to the foregoing description to indicate the scope of the invention.

75 What I claim is:

1. In a device of the kind described, the com-

bination of a fixed mold member, and a pair of movable mold members coactingly connected thereto and mutually counterbalanced in all positions to which the movable mold members may be moved, all points on said movable mold members moving in circular paths about axes fixed relatively to the said fixed mold member.

5. In a device of the kind described, a frame, a mold member fixed to said frame, and two movable mold members coactable with said fixed mold member for forming casting molds therewith, each of said movable mold members being joined to and counterbalanced by the other of said movable mold members in all positions to which the movable mold members may be moved, all points on said movable mold members swinging in circular paths about separate axes fixed relatively to the frame.

6. In a device of the kind described, the combination of a frame, a mold member fastened to said frame and having two mold faces and two movable mold members coactingly pivoted on the frame in counterbalanced relation in all positions to which the movable mold members may be moved, all points on said movable mold members moving in circular paths about axes fixed relatively to the frame.

7. In a device of the kind described, the combination of a frame, a fixed mold member and two movable mold members rockingly mounted on pivots fixed to said frame, all points on said movable mold members moving in circular paths about axes fixed relatively to the frame, the movable mold members being operatively and counterbalancingly joined to each other in all positions to which they may be swung by means, whereby as one of said movable mold members is moved to operative vertical position for casting, the other of said movable members will be moved to horizontal position.

8. In a device of the kind described, the combination of a frame, two movable mold members, all points on said movable mold members moving in circular paths about separate axes fixed relatively to the frame, a fixed mold member, and means pivoted to and connecting said movable mold members whereby each of said movable mold members will serve to swing and counterbalance in all positions to which the other of said movable mold members may be swung for engagement with and disengagement from the fixed mold member.

9. In a device of the kind described, the combination of a frame, a mold member fixedly secured thereto, a pair of other mold members

swingably connected to the fixed mold member, all points on said last mentioned mold members moving in a circular path about adjacent axes fixed relatively to the support, and means pivotally joining the last mentioned said pair of mold members, whereby either of the pair of movable mold members will be supported in equilibrium by the other in all positions to which they may be swung.

10. In a device of the character described, a fixed mold member, a movable mold member, a gauge, an arm adjustably connected to said gauge, resilient means for maintaining said arm and consequently said gauge in operative position relatively to the movable mold member, and instrumentalities arranged on said gauge and said movable mold member to adjust the gauge in two different directions and to remove same from the movable mold member when desired.

11. In a device of the character described having a mold member, the combination with said mold member, of a gauge, a member securable to said gauge, a slot formed in said member, means secured to said gauge and slidable within said slot for moving the gauge and member relatively to each other, a second slot formed in the member, means adjustably mounted in said last mentioned slot, and resilient instrumentalities connected to said last mentioned means and coactingly engaged with means on said mold member.

12. In mechanism of the character described, a frame, a mold member fixedly secured to the frame, a second mold member movably connected to said frame, a gauge swingably connected to the movable mold member and adjustable longitudinally and transversely thereof, instrumentalities detachably connecting the gauge to the movable mold member, and a spring adapted to operatively and yieldingly maintain the gauge against the movable mold member.

13. In a device of the character described, the combination of a fixed mold member, two movable mold members hingedly connected to swing bodily about points fixed relatively to the fixed mold member, and link means pivotally connected at one end to an axis fixed relatively to one movable mold member and at the other end to an axis fixed relatively to the other mold member; said axes being remote from the centers of gravity of the movable mold members, and so positioned as to constrain said movable mold members to move in unison and inherently in counterbalanced relation with each other in all positions to which they may be swung.

WILLIAM F. HUCK. 55
